UNITED STATES PATENT OFFICE.

WALTER P. ALBERT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed August 27, 1923. Serial No. 659,515.

To all whom it may concern:

Be it known that I, WALTER P. ALBERT, a citizen of the United States of America, residing at East Orange, in the county of 5 Essex, State of New Jersey, have invented certain new and useful Improvements in Telephone Systems, of which the following is a full, clear, concise, and exact description.

10 This invention relates to telephone systems and particularly to machine switching systems of small capacity such as those used in private branch exchange installations.

15 The object of the invention is to secure the maximum efficiency from small rotary switches and to produce a small capacity system which will be simple, and easily maintained.

20 A feature of the invention resides in the use of a circuit arrangement in combination with a simple rotary switch whereby all of the active terminals may be used for line connection.

25 Another feature resides in the provision of a link circuit for extending connections comprising a switch and means responsive to a plurality of trains of impulses for setting said switch, the switch itself being directly responsive to but a single one of 30 said trains of impulses.

35 Heretofore similar systems have employed certain of the active contacts as switching positions and the switch was first directly set on such contacts before being moved to connection with the wanted terminals. In the present arrangement greater efficiency is obtained by utilizing such contacts for line numbers and the wear and tear on the apparatus is at the same time reduced by 40 carrying on such necessary switching operations by auxiliary and more easily maintained apparatus.

45 The drawings when placed Fig. 2 to the right of Fig. 1 diagrammatically illustrate a circuit arrangement embodying this invention. Fig. 1 represents a calling line and a finder switch together with an allotter switch for preselecting an idle finder. Fig. 2 represents a connector switch and all of 50 its associated relays together with two called lines.

The finder switch comprises a small step-by-step switch having six brushes and six corresponding rows of terminals. Since it

requires but three brushes to take care of 55 the connections to a line, the finder switch is divided into two sections of three brushes each leading to two groups of lines. The substation 100 is shown as connected to the terminals of the first group of lines, such connection being indicated through the group relay 102 having a conductor leading to the allotter brush A¹. The second group of 60 lines is represented by the group relay 101 having a conductor leading to the allotter brush A³.

When the subscriber at station 100 removes his receiver from its switchhook a circuit is established over the loop of the calling substation and through the windings of 70 line relay 103 causing this relay to attract its armatures. Through its left-hand armature, relay 103 causes the energization of group relay 102 and through its right-hand armature and resistance 104 it places a low 75 resistance battery potential on the sleeve conductor of the calling line. The energization of relay 102 results in the establishment of a circuit from ground, right-hand armature and front contact of relay 102, brush A¹, 80 which is resting on the terminal corresponding to an idle line finder, the armature and back contact of relay 105, armature 106 and back contact of relay 107, back contact and armature of stepping magnet 108, winding 85 of magnet 108 to battery and ground. Magnet 108 becomes energized in this circuit and attracts its armature thereby breaking its own circuit. Upon its deenergization magnet 108 moves the brushes shown in a vertical 90 line beneath it to their first active contacts. Upon such movement of the brushes the off-normal contact 109 is closed, whereupon a circuit is established from ground, inner 95 left-hand armature and back contact of relay 200, off normal contact 109, back contact and armature of magnet 108, winding of magnet 108 to battery and ground, such circuit being in parallel with the circuit hereinbefore described for the energization of 100 magnet 108 and being provided for the purpose of rotating the brushes back to their normal position should the call be abandoned before the calling line is reached by the finder switch. Under normal conditions, 105 magnet 108, being in a self-interrupting circuit, will cause the brushes of the finder switch to move step-by-step until the calling

line is reached by the brushes of the finder switch.

line is reached, whereupon a circuit will be established from ground, right-hand armature and front contact of relay 102, brush A¹, winding of relay 105, brush FS, resistance 104, front contact and right-hand armature of line relay 103 to battery and ground whereupon relay 105 becomes energized. The energization of relay 105 extends the ground at its armature through its front contact to the winding of relay 107 so that the calling subscriber's line is now extended to the windings of line relay 201 and this relay becoming energized establishes a circuit for the holding relay 202, which in turn, causes the energization of relay 200. The energization of relays 105 and 200 cut off the ground connection to the stepping magnet 108 so that this magnet now ceases its operation leaving the brushes FT, FR and FS on the terminals of the calling line. Relay 107 now locks in a circuit from ground, the outer left-hand armature and front contact of relay 200, armature 110 of relay 107, winding of relay 107 to battery and ground. A circuit is also established from ground, the inner left-hand armature and front contact of relay 200, armature 111 of relay 107, brush, FS, winding of cut-off relay 112 to battery and ground. It will be noted that the cut-off relay is marginal and that while ground was extended through the winding of relay 105, it did not become operated, but that when a direct connection from ground was placed on the sleeve conductor of the line, the cut-off relay became energized. A direct ground placed on the brush FS is also extended to the other terminal of relay 105 so that this relay now becomes shunted and consequently deenergizes. At this time a ground is also extended from the inner left-hand armature and front contact of relay 200, brush A², armature and back contact of magnet 113, winding of magnet 113 to battery and ground, whereupon this magnet becomes energized and moves the brushes A¹, A² and A³ forward. As long as grounded connections are found on the terminals traversed by brush A², magnet 113 will continue to step such brushes, but when an idle finder switch is reached, magnet 113 ceases its operations. The energization of the cut-off relay 112 causes the deenergization of line relay 103 and the consequent deenergization of the group relay 102, so that the connection is now in a stable condition awaiting the sending of impulses from the calling substation.

According to the scheme employed in the connector switch there are four groups of lines numbered respectively 10 to 49. This switch, like the finder switch, is a simple rotary type switch having six brushes which are divided into two sets of three each. The first set of brushes has access to lines 10 to 29 and the second set of brushes has access

to lines 30 to 49, inclusive. There is a primary normal position on which all brushes normally rest and a secondary normal position to which all brushes may be driven under certain conditions. Between the primary and secondary normal positions the first set of brushes reaches lines Nos. 10 to 19 and the second set of brushes reaches lines 30 to 39. Between the secondary normal position and primary normal position, the first set of brushes reaches lines 20 to 29 and the second set of brushes reaches lines 40 to 49. Thus when the first digit is 1, the first set of counting relays 208 and 209 will be energized with the result that the switch remains in its normal position and the first set of brushes is rendered effective.

The digit 1 is represented by a single short interruption of the calling line circuit which results in the momentary de-energization of relay 201, whereupon a circuit is extended from ground, the armature and back contact of relay 201, the front contact and right-hand armature of holding relay 202, winding of slow releasing relay 203, inner left-hand armature and back contact of relay 204, outer left-hand armature and back contacts of relays 205, 206, 207 and 208, winding of relay 209 to battery and ground. Relays 203 and 209 become energized in this circuit and establish a connection from ground, the alternate contact and right-hand armature of relay 203, back contact and outer left-hand armature of relay 207, armature and front contact of relay 209, winding of relay 208, winding of relay 209 to battery and ground. Relay 208 is, however, short-circuited at this time so that it does not become energized until relay 201 again attracts its armature. When this happens the ground extended over the armature and back contact of relay 208 is removed and relay 208 becomes energized and relay 209 remains energized in the circuit last traced.

Another circuit is also extended from ground, the outer right-hand armature and front contact of relay 200, the alternate contact and left-hand armature of relay 203, winding of relay 213 to battery and ground. Relay 213 becomes energized and locks in a circuit from ground, the outer right-hand armature and front contact of relay 200, the inner left-hand armature and back contact of relay 214, the front contact and left-hand armature of relay 213, winding of relay 213 to battery and ground. After a short interval relay 203 becomes deenergized whereupon a circuit is established from ground, outer right-hand armature and front contact of relay 200, normal contact of the left-hand armature of relay 203, front contact and outer right-hand armature of relay 213, winding of relay 204 to battery and ground. Relay 204 becomes energized and locks in a circuit from ground outer left-hand arm-

ture and front contact of relay 204, front contact and outer right-hand armature of relay 213, winding of relay 204 to battery and ground. At the same time the ground 5 is removed from the windings of relays 208 and 209 so that these relays now become deenergized. It will be noted that the winding of relay 203 is now extended through the inner left-hand armature and front 10 contact of relay 204 to the winding of stepping magnet 215, so that upon the receipt of the next series of impulses the stepping magnet will be energized to move the brushes of the connector switch forward. It will 15 further be noted that the switch has not been moved in response to the first digit.

When the first digit is 2 the line relay 201 will be deenergized twice in quick succession. Upon the first deenergization relays 20 208 and 209 will become energized in the manner hereinbefore described. Upon the second deenergization of relay 201 ground will be extended over the outer right-hand armatures and back contacts of relays 205, 25 206 and 207 and thence over the right-hand armature and front contact of relay 208 to the winding of relay 210. Upon the following energization of relay 201 a circuit 30 will be established from ground, outer right-hand armature and front contact of relay 200, inner left-hand armature and back contact of relay 214, outer left-hand armature and back contact of relay 206, armature and front contact of relay 210, winding of 35 relay 207, winding of relay 210 to battery and ground, whereupon relay 207 will become energized in series with relay 210 and relays 208 and 209 will be deenergized. During the energization of relay 203 relay 40 213 becomes energized in the manner hereinbefore described and upon the deenergization of relay 203, relay 204 becomes energized in the manner hereinbefore described. In addition to this a circuit will now be 45 established from ground, normal contact of the right-hand armature of relay 203, the inner left-hand armature and front contact of relay 207, back contact and armature of relay 216, back contact and armature of 50 magnet 215, winding of magnet 215 to battery and ground. Magnet 215 is now included in a self-interrupting circuit and will, consequently, move the brushes of the connector switch step by step until relay 216 55 is energized to open the circuit just described. Relay 216 will be energized in a circuit from ground, normal contacts of the right-hand armature of relay 203, inner left-hand armature and front contact of relay 60 207, outer left-hand armature and back contact of relay 214, front contact and inner right-hand armature of relay 213, normal contacts of the innermost right-hand armature of relay 217, brush CS and its contact 65 corresponding to the secondary normal posi-

tion, winding of relay 216 to battery and ground. Thus in response to the digit two there is an automatic movement of the connector switch.

When the first digit is 3 the line relay 70 201 will be deenergized three times quickly in succession with the result that counting relays 206 and 211 will be energized and the two sets of counting relays corresponding to digits 1 and 2 will become deenergized. Relays 213 and 204 will be energized in the manner previously described. In addition to this a circuit will be established from ground, the normal contacts of the right-hand armature of relay 203, the 75 inner left-hand armature and front contact of relay 206, winding of relay 217 to battery and ground. Relay 217 locks up in a circuit from ground, the outer left-hand armature and front contact of relay 200, 80 left-hand armature and front contact of relay 217, winding of relay 217 to battery and ground. Thus the brushes of the connector switch will be left in their primary normal position but the relay 217 will become 85 energized to render the brushes CT¹, CR¹ and CS¹ effective.

When the first digit is 4 the brushes will be moved to their second manual position and the relay 217 will become energized 90 thereby rendering the brushes CT¹, CR¹, and CS¹ effective from their second normal position.

Let us now assume that the first digit was 2 and that following the movement of the 100 brushes to their second normal position in the manner hereinbefore described, the calling subscriber now sends a series of three impulses. Relay 201 will now become deenergized three times quickly in succession. Upon each deenergization of relay 201 a circuit is established from battery and back contact of relay 201, front contact and right-hand armature of relay 202, winding of relay 203, inner left-hand armature and front 105 contact of relay 204, winding of magnet 215 to battery and ground. Each deenergization of relay 201 causes the energization of magnet 215 so that the brushes are stepped forward three steps from their second normal position and come to rest on the terminals of line 218 which will be, according to the numbering scheme just described, station No. 23. Upon the energization of slow-releasing relay 203 during the sending of 110 the second digit a circuit is established from ground, alternate contacts of the right-hand armature of relay 203, right-hand armature and front contact of relay 204, winding of relay 214 to battery and ground, whereupon relay 214 becomes energized. As the brush CS comes to rest on the terminals of the called line and relay 203 becomes deenergized, relay 213 becomes deenergized 115 and a circuit is established from the sleeve 120

conductor of the called line, through the brush CS, the normal contacts of the innermost right-hand armature of relay 217, the inner right-hand armature and back contact of relay 213, inner right-hand armature and front contact of relay 214, left-hand winding of relay 219 to battery and ground. If the called line is busy ground will be found on the sleeve conductor and relay 219 will become energized, locking up through its right-hand winding its front contact and inner left-hand armature to the ground at the front contact and outer right-hand armature of relay 200, whereupon busy tone will be extended from the source of busy tone 220, through the front contact and left-hand armature of relay 219, condenser 221, the right-hand winding of impedance coil 222 to battery and ground, whence by induction the busy tone is transmitted to the calling line.

If, on the other hand, the called line is idle, then the battery connection from the cut-off relay 223 is opposed to the battery connection to relay 219 and this relay does not momentarily become energized. Shortly, thereafter, relay 214 becomes deenergized whereupon a circuit is established from ground, back contact and inner right-hand armature of relay 214, back contact and inner right-hand armature of relay 213, normal contacts of the innermost right-hand armature of relay 217, brush CS, winding of relay 223 to battery and ground so that the called line is now made busy.

During the energization of relay 214, a circuit is established from ground, outermost right-hand armature and front contact of relay 200, innermost left-hand armature and front contact of relay 214, right-hand winding of ringing relay 224 to battery and ground. This relay locks up in a circuit from ground, the outermost right-hand armature and front contact of relay 200, the innermost right-hand armature and back contact of relay 219, the back contact and armature of relay 225, the front contact and right-hand armature of relay 224, left-hand winding of relay 224 to battery and ground. Now upon the deenergization of relay 214 a circuit is established from ground off normal contact 226, inner right-hand armature and front contact of relay 200, upper right-hand armature and back contact of relay 214, winding of relay 227 to battery and ground. Through the energization of relay 227 a circuit is established from the source of ringing current 228, winding of relay 225, front contact and inner left-hand armature of relay 224, front contact and right-hand armature of relay 227, middle right-hand armature and back contact of relay 217, brush CR, and thence over the loop of the called substation, brush CT, back contact and outermost right-hand armature

of relay 217, front contact and left-hand armature of relay 227, outer left-hand armature and front contact of relay 224 to ground so that the bell of the called substation is rung. During the ringing of the called substation a small amount of ringing current is shunted over a path from the right-hand armature of relay 227, back contact and left-hand armature of relay 219, condenser 221, right-hand winding of impedance coil 222 to battery and ground, whence by induction a ringing tone is transmitted to the calling substation. The current flowing in the ringing circuit is insufficient to cause the energization of relay 225 until the called subscriber removes his receiver from the hook, whereupon the flow of current is increased to the point where relay 225 attracts its armature, whereupon opening the locking circuit of relay 224 and cutting off the ringing current, at the same time, establishing a direct talking connection between the two subscribers.

At the end of the conversation the calling subscriber at substation 100 replaces his receiver on its hook, whereupon the relay 201 becomes deenergized. In a short interval relay 202 becomes deenergized and causes the deenergization of relay 200. This relay removes the ground which is holding relay 107 energized whereupon this relay retracts its armatures. A circuit is also established from ground, the inner left-hand armature and back contact of relay 200, off-normal contact 109, back contact and armature of magnet 108, winding of magnet 108 to battery and ground. This magnet being now in a self-interrupting circuit moves the brushes of the finder switch to their normal position, whereupon the off-normal contact 109 breaks the circuit of magnet 108 and the finder switch comes to rest. At the same time a circuit is established from ground, off-normal contact 226, the inner right-hand armature and back contact of relay 200, the back contact and armature of magnet 215, winding of magnet 215 to battery and ground. Magnet 215 being in a self-interrupting circuit moves the brushes of the connector switch to their primary normal position, whereupon the off-normal device 226 breaks the circuit of magnet 215 and the connector switch comes to normal position. Thus the connection is restored to normal.

What is claimed is:

1. In a telephone system, a link circuit for extending connections comprising a switch having access to a plurality of groups of lines, a set of counting relays for making a group selection, and means for controlling said switch to make an individual line selection.
2. In a telephone system, a switch having a plurality of sets of brushes each serving a plurality of groups of line terminals, a set

of counting relays individual to said switch for selecting a particular set of brushes and a particular group of line terminals and means for thereafter directly controlling 5 said switch to make an individual line selection.

3. In a telephone system, a switch having a primary and a secondary normal position and a plurality of sets of brushes, a plurality 10 of relays individual to said switch for selecting a particular set of brushes and causing said switch to move to its secondary normal position and means for thereafter directly controlling said switch to make 15 an individual line selection.

4. In a telephone system, a switch having a primary and a secondary normal position physically separated by groups of line terminal positions and a plurality of sets of brushes, lines connected to terminals at all 20 other positions of said switch, said lines being divided into groups defined by said normal positions and said different sets of brushes, means for making a group selection and means for directly moving said 25 switch to make an individual line selection.

In witness whereof, I hereunto subscribe my name this 23 day of August A. D., 1923.

WALTER P. ALBERT.
